Patented July 4, 1922.

UNITED STATES PATENT OFFICE.

CHARLES E. GLESSNER, OF PORTLAND, OREGON.

TANK AND CLOSURE.

1,421,454.

Specification of Letters Patent. Patented July 4, 1922.

Application filed September 29, 1919. Serial No. 327,110.

To all whom it may concern:

Be it known that I, CHARLES E. GLESSNER, a citizen of the United States, residing in Portland, in the county of Multnomah and 5 State of Oregon, have invented a new and useful Tank and Closure, of which the following is a specification.

My invention relates more particularly to a tank suitable for use in dehydration process, although it is apparent that it may be used to an equal advantage in any of the other arts in which an inexpensive, strong, air-tight and sanitary receptacle is required.

The object of my invention is to provide 15 an exceedingly economical means for maintaining a vacuum, and a perfect insulation against the loss of heat by radiation in an enclosure of relatively large proportions, and to provide such enclosure with a hermetically sealed closure means which is simple of operation.

I attain these objects in the manner described in the following specification and illustrated in the accompanying drawing, of 25 which:

Figure 1 is a longitudinal view of the tank showing its foundation broken away in section, as well as a portion of the closure frame, for the sake of clearness; Figure 2 30 is a front elevation of the apparatus taken in section through the pit in front of the tank; Figure 3 is a section along the line 3—3 in Figure 1 showing the relation of the concrete wall of the tank and its inner and 35 outer laggings and insulations, together with a vacuum producing pipe for the tank proper, and a second vacuum producing pipe for the area between the inner and outer laggings, and also showing the movable support for the tank; Figure 4 is an enlarged detail showing an expandible air-tight joint for the various sections of the lagging, both on the walls of the tank and its end enclosure members. In Figure 4 is 40 also indicated a relief valve for equalizing pressures, and also the means for hermetically sealing the closure upon the tank; Figure 5 is a partial plan showing the closure guide means and holding screw.

50 Similar letters and numbers of reference refer to the same or similar parts throughout the several views.

A¹ is the wall of a cylindrical tank one end of which is closed by the head A² and 55 the other by the closure member A³. The tank itself is supported by means of a fixed

pedestal A⁴ and a movable pedestal A⁵ which rests on the rollers A⁶. The closure member A³ is supported by the counterweight A⁷ to which it is joined by the cable A⁸ passing over the sheaves A⁹. Pedestals A⁴ and A⁵ rest on the floor A¹⁰. At the rear or closed end of the tank A¹ is a pit A¹¹ for the counterweight A⁷. In front of the tank is a pit A¹² for the closure A³.

The entire outside of the tank and the closure are covered by a hermetically sealed lagging H¹ which passes between the tank walls A¹ and the pedestals A⁴ and A⁵. This inside lagging H² is joined to the outside 65 lagging H¹ in a manner to entirely surround the structure of the tank itself, and is provided with a vacuum pipe line H³ for exhausting whatever air remains between the two laggings in order to improve its insulating qualities, and this pipe line is provided with a gauge H⁴ for the purpose of indicating the amount of pressure remaining 70 between the laggings H¹ and H². H⁵ is a vacuum producing pipe extending to the 75 interior of the tank and upon which is mounted the gauge H⁶ which indicates the amount of pressure within the tank. H⁷ is a check valve mounted on the inside of the inside lagging H², which has for its purpose 80 the prevention of a greater vacuum existing within the tank than exists within the tank walls, inasmuch as it would plainly destroy the inside lagging H² should the tank 85 vacuum exceed the vacuum between the laggings. H⁸ is a vacuum producing pump on the closure member A³. H⁹ is gauge on 90 closure member.

C¹ is the closure frame, from the upper 95 side of which are swung the links C² from which is suspended the closure A³. It will be understood that the closure member A³ is also hermetically covered with a metal lagging, as is the tank itself, and that the means for supporting said closure within the frame C¹ will be such as to prevent the passage of 100 any air into the space between the lagging which surrounds the closure. It will also be observed in Figure 1 that when the closure A³ is in place that it is not directly underneath its point of support:—in other words that when the closure A³ is not held against the face of the tank walls A¹ it will be held away from same by its own weight. On the 105 sides of the closure A³ are the lugs C³ which are used as a point of bearing for the screws C⁴ which are used to hold the closure against

the tank until it has been sealed by the vacuum from within. Along the sides of the closure frame C^1 are the grooves C^5 which engage the T members C^6 which serve as a guide for the frame C^1 and also as a support for the screws C^4 . On the upper side of the frame C^1 are mounted the rails C^7 which serve as connecting rails between the rails C^8 within the tank A^1 and the rails C^9 outside of the tank A^1 . The upper ends of the T members C^6 are connected by the girder C^{10} , which serves as a stop for the closure frame C^1 in its uppermost position and also as a support for the sheaves A^9 .

15 In order to accommodate the different expansions of the laggings H^1 and H^2 I have provided expansion joints indicated in Figure 1, whose peculiar construction enables the various sections of the laggings to expand and contract without destroying the hermetical seal of the component members. In this joint the edges of the individual sheets which form the laggings are crimped to form the two sides L^1 and L^2 in a manner 25 that the point L^3 touching a similar point on the adjacent sheet and the area between the sides L^2 , forms a V shaped trough which is filled with solder L^4 thereby producing an expansible air-tight joint.

30 When the closure A^3 is in the position shown in Figure 4 and held in place by the screws C^4 the pneumatic gasket M^1 is inflated and protrudes from the annular groove M^2 and comes in contact with the inner lagging on the closure A^3 , thereby providing a seal capable of resisting atmospheric pressure.

It will be observed that when the apparatus is in the position shown in Figure 1 40 and it is desired to open same, it is first necessary to reduce the vacuum within the tank A^1 and then release the screws C^4 which will permit the closure member A^3 to swing away from the face of the tank A^1 45 when any downward pressure upon the closure or its frame will cause both to be lowered into the pit A^{12} , which, of course, will raise the counterweight A^7 to the position shown in the dotted lines in Figure 1.

50 O^1 is a drain pipe and air inlet, which, together with the pipe O^2 , permits of circulation of rarefied air through the tank, either from an auxiliary condensing tank or directly, by means of a pump uniting O^1

and O^2 . O^3 is a felt lining separating the 55 lagging from the concrete walls of the tank and closure and serves as insulation and to reduce the friction between the concrete and metal lagging.

I have specified the walls of this device as 60 being constructed of concrete, but it is evident that any other material providing sufficient strength may be used instead of concrete, without departing from the spirit of my invention.

65 I claim—

1. The combination of a tank and closure member with an expansible metal covering 70 hermetically enclosing the inner, outer and end surfaces of the structure of said tank, a vacuum creating means adapted to exhaust the air from between said tank coverings, an expansible metal covering hermetically enclosing the structure of said closure member, a vacuum creating means adapted to 75 exhaust the air between the covering which surrounds said closure member, a means for exhausting the air from within the tank itself, and a means for sealing the union of said tank member and said closure 80 member.

2. The combination of a concrete tank, an inner and outer lagging which completely surrounds the structure of said tank, supporting members for sustaining said tank 85 in a horizontal position, a closure means consisting of a concrete member covered internally and externally with hermetically joined lagging, a means for suspending said closure member away from and in front of 90 the open end of said tank, screws for holding said closure member against the front of the open end of said tank, a counterbalanced frame mounted between guides and supporting said closure member, means for establishing and measuring a partial vacuum 95 which is held within the inner and outer lagging of the tank and its closure, means for preventing the destruction of the inner lagging, consisting of check valves opening 100 into said tank and mounted on an inner lagging, a means for sealing the union of said tank and said closure, consisting of a pneumatic gasket placed within an annular groove around the open end of said tank 105 member, and a means for inflating said pneumatic gasket.

CHARLES E. GLESSNER.
